UNITED STATES PATENT OFFICE.

OMER L. DOWNING, OF SOUTH NORWOOD, OHIO.

CONCRETE INSERT.

Application filed July 25, 1927. Serial No. 208,352.

This invention relates to concrete inserts, and its general object is to provide an insert adapted to be fixedly embedded in concrete and the like for the reception of bolts and 5 the like in a manner whereby a bolt or the like can be secured therein or removed therefrom with very little effort.

A further object of the invention is to provide an insert for concrete work that is 10 in the nature of a housing adapted to receive bolts and the like of various sizes, the parts of the insert being interchangeable for that purpose before and after the insert is fixed in the concrete.

15 Another object of the invention is to provide a concrete insert that can be set and fixed in any desired position before the concrete is poured thereabout, and be retained in that position after the concrete sets.

20 This invention also consists in certain other features of construction and in the combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several 30 views, and in which:

Figure 1 is a sectional view taken approximately on line 1—1 of Figure 2 and illustrates one form of my invention with the same embedded in a ceiling.

35 Figure 2 is a sectional view taken approximately on line 2—2 of Figure 1.

Figure 3 is a bottom plan view of the insert as shown in Figures 1 and 2.

40 Figure 4 is a sectional view taken on line 4—4 of Figure 1.

Figure 5 is a detail view of one of the plates used in this form of the invention.

45 Figure 6 is a sectional view taken through a slightly modified form.

Figure 7 is a perspective view showing a fragmentary portion of one of the sections and the recess for providing the weakened portion of said housing.

50 Referring to the drawings in detail the letter A indicates concrete which is adapted to receive my insert in the manner as best shown in Figures 1 and 2 of the drawings, and in the form of the invention as shown in Figures 1 to 5 inclusive, the reference numeral 1 indicates a housing which is of a receptacle type and includes inclined side walls

2 and 3, connected at their ends with an inner wall 4 and an outer wall 5. The housing is formed by a pair of sections which are identical in construction and have extending 60 from their side walls apertured ears 6 adapted to receive a bolt and nut connection 7 for securing the sections together in housing formation as best shown in Figure 4 of the drawings. The housing also includes walls 8 and 65 9 from which extend in spaced parallel pairs lugs 10 which are recessed as at 11 for the purpose of receiving nails or other fastening means for securing the housing in place before pouring the concrete thereabout as 70 will be apparent.

Extending from the inner wall 4 are projections 12 which have formed on their outer ends strips 13 and these strips and projections 12 are substantially reinforced by ribs 75 14 as best shown in Figures 1 and 2 of the drawings. The projections and strips thereof are adapted to strengthen the construction and to firmly hold the same in the concrete.

Disposed in the forward corners within 80 the housing are extensions 15 arranged in parallel cooperating pairs and which are provided with bearing bores 16 to receive trunnions 17 formed on one of the ends of plates 18 which by this construction are mounted 85 for pivotal movement in the housing and are provided with semi-circular recesses 19 in their free ends so that said plates cooperate for securing the headed end of a bolt or the like in the housing as will be apparent. 90

The outer wall 5 of the housing is substantially thicker than the remaining walls thereof, and this outer wall 5 is provided with an interiorly centrally disposed recess 20 so as to weaken the wall 5 whereby this 95 weaken portion which is indicated by the reference numeral 21 can be removed after the housing is embedded in the concrete so as to allow the reception of headed bolts and the like within the housing as will be apparent. 100

In Figure 6 I have illustrated a slightly modified form of the invention and while this form includes the sectional housing as indicated by the reference numeral 22 together with the reinforced projections and strips 105 for securing the same in concrete, it will be noted that the extensions 15 have not been included therein as in this form of the invention the bolt securing plates are adapted to be inserted after the housing has been fixed 110 in the concrete. The plates of this form of the invention are indicated by the reference

numeral 23 and have their respective side edges provided with recesses which cooperate to secure a bolt and the like in the housing. It will be noted that the recesses 24 are relatively smaller than the recesses 25 but in any event the recesses of the same size are adapted to cooperate as shown in Figure 6, and by this construction bolts of various sizes can be fixed in the housing as the plates 10 will be recessed accordingly. The plates 23 are loosely mounted in the housing and therefore it can be removed and interchanged as desired.

From the above description and disclosure 15 of the drawings, it will be obvious that I have provided a concrete insert which is adapted to detachably receive bolts and the like, and the heads of the bolts are placed in the housing after the weakened portion 21 is removed therefrom and arranged so that the plates 18 or 23 engage the head as shown in Figures 1 and 6, which will of course prevent the bolt from being removed until such removal is desired. When the housing is disposed in a ceiling as shown in Figures 1 and 25 2, it will be obvious that the inclined walls 2 and 3 will cause the plates 18 to always remain under the action of gravity and when the bolt as shown at B is placed in the housing 30 and positioned as shown in dotted lines in Figure 1, the plates will drop by gravity to their normal position as shown in full lines and thus be disposed between the head and the front plate 5.

35 It is thought from the foregoing description that the advantages and novel features of my invention will be readily apparent.

I desire it to be understood that I may make changes in the construction and in the 40 combination and arrangement of the several

parts, provided that such changes fall within the scope of the appended claims.

What I claim is:

1. A concrete insert of the character described comprising a housing having a recessed front wall to provide a weakened portion adapted to be removed when the housing is set in concrete, recessed plates arranged in said housing and cooperating for detachably securing a bolt therein. 45 50

2. A concrete insert of the character described comprising a sectional housing, apertured ears formed on each section, means arranged in the apertures of said ears for fixing the sections together in housing formation, recessed lugs formed in said housing projections formed with said housing and cooperating for retaining said housing in concrete, recessed plates adapted to be arranged in said housing and cooperating for detachably securing a bolt therein extensions formed in the forward corners of said housing and being provided with bearing bores, and trunnions formed on one of the ends of the plates and being mounted in the bearing 60 65 bores. 55

3. A concrete insert of the character described comprising a sectional housing, means for securing said sections together in housing formation, reinforced projections 70 extending from said housing, an interiorly recessed inner wall included in said housing to provide a centrally disposed weakened portion adapted to be removed when said housing is set in concrete and plates provided with recesses of various sizes and being adapted to cooperate for detachably securing a bolt in said housing. 75

In testimony whereof I affix my signature.

OMER L. DOWNING.
